UNITED STATES PATENT OFFICE.

CHARLES E. McMANUS, OF NEW YORK, N. Y.

CARRIER FOR CORK-ROD BAKERS.

1,409,223.

Specification of Letters Patent. Patented Mar. 14, 1922.

Application filed May 28, 1921. Serial No. 473,426.

To all whom it may concern:

Be it known that I, CHARLES E. McMANUS, a citizen of the United States, residing at the borough of Manhattan, in the city 5 county, and State of New York, have invented certain new and useful Improvements in Carriers for Cork-Rod Bakers, of which the following is a specification, reference being had therein to the accompanying drawings, 10 which form a part thereof.

My invention relates to carriers for cork rod bakers, and more particularly to a structure facilitating the mounting and removal of metallic tubes packed with composition 15 cork in the baking or vulcanizing machine, while at the same time utilizing the expansion of the composition within the tube, while under heat in the baker, to cause compaction of the mass of the composition in the 20 tube, instead of elongation of the rod.

In the manufacture of cork rods for use in the production of cushion disks for bottle caps and other purposes, it is the practice to pack a composition formed of granules of 25 cork having a thin coating of binding material thereon, in metal tubes. The binder is of a nature which when subjected to an elevated temperature, will first become adhesive, when the critical temperature is reached, 30 and thereafter be vulcanized or cured in practically the same manner as vulcanized rubber compounds, resulting in a highly resilient cork product which is used as a substitute for natural cork for various purposes. 35 In packing the metallic tubes with this composition, the cork is fed to the tube in a sequence of small measured batches, each batch being packed after being fed to the tube, a condition which leaves one end of the tube 40 empty for a short distance. Ordinarily the end of the tube first packed is closed by a removable plug.

During the baking or vulcanizing operation, the elevated temperature will cause the 45 expansion of the cork composition in the tube and the main purpose of my present invention is to so construct the carrier for the tubes containing the cork rods, that this expansion will be utilized to secure the desired 50 intimacy of the various granules of binder coated cork with the two-fold object of securing a permanent bond between adjoining granules and a greater density in the mass forming the rod, while at the same time facilitating the mounting and removal of the 55 tubes in the baking machine.

The carrier of my invention embodies therein spaced plates, one of which has a stud thereon adapted to enter the end of the tube in which the cork was last packed, and 60 to extend thereinto for a distance sufficient to engage the end of the cork rod, the other plate being slotted to receive the opposite end of the tube. The stud must be so formed as to permit the end of the tube to pivot 65 upon same, thus permitting the tubes to be rapidly placed in the baker and rapidly removed therefrom, it being possible, and preferable, to so construct the carrier as to permit such mounting and removal of the tubes 70 in groups.

The invention consists primarily of a carrier for cork rod bakers embodying therein carrier members, oppositely disposed plates carried thereby and spaced apart a distance 75 substantially equalling the length of the metallic tubes containing the cork rods, one of said plates having a slot formed in that face thereof presented toward the other plate, and a stud carried by the other plate having a 80 reduced stem and projecting toward said slotted plate, whereby a tube may be mounted in said carrier by inserting the empty end thereof over said stud until the head of the stud is in substantial engagement with the 85 cork composition in the tube, and dropping the other end of said tube into said slot with a pivotal movement of the tube about said stud; and in such other novel features of construction and combination of parts as are 90 hereinafter set forth and described, and more particularly pointed out in the claims hereto appended.

Referring to the drawings,

Fig. 1 is a front view of a carrier embodying my invention, adapted to receive sixteen tubes, two tubes being shown mounted therein with one end thereof shown in section;

Fig. 2 is a face view of the stud carrying plate, upon an enlarged scale, on the line 100 2-2 of Fig. 1;

Fig. 3 is a detail side elevation of one of the studs upon a still larger scale; and

Fig. 4 is a face view of the slotted plate, on the line 4-4 of Fig. 1. 105

Like letters refer to like parts throughout the several views.

In the embodiment of my invention shown in the drawings, *a* and *b* indicate carrier chains which are adapted to convey the tubes 110 containing the composition cork to be baked, cured or vulcanized, through the baking

oven or vulcanizer. At spaced distances upon this chain are carriers adapted to hold the tubes containing the composition during their passage through the baker or vulcanizer. Since each of these carriers is a duplicate of every other, the showing of the drawings and the description are limited to but one of these carriers.

Carried by opposite links of the chains *a* 10 and *b* respectively are brackets *c* and *d* between which extends a stay rod *e* carrying a stud plate *f* and a slotted plate *g*.

The chain *a* passes about a sprocket wheel *h* while the chain *b* passes about a sprocket 15 wheel *i*. The plates *f* and *g* are spaced apart a distance substantially equaling the length of the tubes *j* containing the cork composition, and have movement with the chains *a* and *b* through the baker or vulcanizer not 20 shown in the drawings.

The plate *f* in the form of the invention shown, has sixteen studs *f'*, grouped upon opposite sides of the rod *c*, arranged in four tiers and spaced apart vertically sufficiently 25 to permit each tube to rest upon the tube below, the plate *g* being provided with four vertically extending slots *g'* in the face thereof each oppositely disposed to a vertical row of studs *f'* and presented toward 30 the plate *f*, the studs *f'* projecting inwardly of said plate *f* or toward the plate *g*.

Each stud *f'* is provided with a reduced stem *f''* and an enlarged head *f'''*, that side of said head presented toward the plate *g* being 35 plane, and the opposite side thereof extending on a curve as at *f''* toward the stem *f''* to form a narrow edge about the head.

The top of the slots *g'* are flared, and the upper corners of the plate *g* are reduced, as 40 shown, to facilitate the mounting of tubes between the plates *f* and *g*.

The slots *g'* are shallow, thus permitting a slight tilting of the tubes *j* to remove the ends adjacent the slots, therefrom.

45 The stem *f''* of each stud *f'* is cylindrical and the diameter of the head is slightly smaller than the inside diameter of a tube *j*.

In operation, the herein described carrier functions substantially as follows:—

50 In charging the baking or vulcanizing machine, the operator places each tube in the machine by slipping the empty end thereof over a stud *f'* and dropping the opposite end in the oppositely positioned slot *g'*, the cork rod in each tube, when the latter is so positioned, being confined between the bottom of the slot *g'* and the head *f'''* of the stud *f'*. In positioning the tube, the upper edge thereof is placed at an angle across 55 the edge of the head and the tube and projected into the space between the edge of the head and the surface of the stud, the tube pivoting upon the head as it is dropped to place. The curved portion *f''* of the head 60 is merely to provide a reduced fulcrum

point about the edge of the head, and the exact contour of this part of the head as well as the exact shape of the stem *f''* is immaterial so long as the stud affords a reduced fulcrum point about which the tube 70 may rock in any direction, and clearance between this fulcrum point and the plate *f* to permit this rocking.

By using a shallow groove *g'*, the tubes *j* 75 may be inserted at any angle and from any position, so long as they clear the side webs of the grooves *g'*, it being a practice for the workman to insert the tubes at an angle so that the end adjacent the plate *g* will clear the webs forming the grooves, then by a lateral movement position them in relation to the groove and permit them to drop to place.

Each carrier is filled as it approaches the 80 operator at the filling end of the baker or vulcanizer, the slow rate of travel of the carrier affording ample time for this operation without stopping the machine.

After each carrier has completed its course 85 through the baker or vulcanizer, the operator at the delivery end of the machine seizes, in the form of the invention shown, a group of eight tubes arranged at the end thereof adjacent the plate *g* and at one side of the rod *e* and raises all of the tubes until the 90 lowermost tube has cleared the webs forming the grooves upon said plate, and then by a lateral or twisting movement removes all of the tubes from the studs *f'* on which they 95 are mounted.

100 While the tubes are in the baker or vulcanizer they are subjected to an elevated temperature for an interval of between one and three hours, according to the binder used, this temperature not only making the 105 binding medium adhesive, but during vulcanization or curing of the binder, expanding the entire contents of the tube without any substantial elongation of the rod, thus causing the expansion of the composition to 110 subject practically every portion of the rod to a pressure which will bring the different granules of cork and their thin coating of binder into such an intimate relation as to 115 secure great density in the product.

The engagement of the plug in each tube with the face of a groove *g'* and the engagement of the exposed end of the rod with a stud *f'* will confine the composition rod so 120 as to secure the effects above referred to, so far as condensation as a result of expansion is secured.

125 It is apparent that an essential characteristic of the invention is the stud *f'*, the head of which affords a fulcrum point for permitting pivotal movement of a tube thereupon, and a reduced stem of a length to afford clearance for the end of the tube projected across said fulcrum point and that without this construction it would be im- 130

possible to mount tubes in, or remove them from, the carrier.

It is therefore not my intention to limit the invention to the precise details of construction shown in the drawings, since the characteristics above referred to may be secured by studs of different contour from those shown, and without departing from the spirit and scope of the invention.

Having described the invention, what I claim as new and desire to have protected by Letters Patent, is:—

1. A carrier for cork rod bakers embodying therein carrier members, oppositely disposed plates carried thereby and spaced apart a distance substantially equalling the length of the metallic tubes containing the cork rods, one of said plates having a slot formed in that face thereof presented toward the other plate, and a stud carried by the other plate having a reduced stem and projecting toward said slotted plate, whereby a tube may be mounted in said carrier by inserting the empty end thereof over said stud until the head of the stud is in substantial engagement with the cork composition of the tube, and dropping the other end of said tube into said slot with a pivotal movement of the tube about said stud.

2. A carrier for cork rod bakers embodying therein carrier members, oppositely disposed plates carried thereby and spaced apart a distance substantially equalling the length of the metallic tubes containing the cork rods, and a plurality of tiers of studs upon one of said plates, projecting towards the other plate, each of said studs having a reduced stem, and said other plate having a plurality of slots therein oppositely disposed respectively to a row of studs included in the different tiers, whereby tubes may be mounted in said carrier by inserting the empty end of each tube over a stud until the head of the stud is in substantial engagement with the cork composition of the tube, and dropping the other end of said tube into said slot with a pivotal movement of the tube about said stud.

3. A carrier for cork rod bakers embodying therein carrier members, oppositely disposed plates carried thereby and spaced apart a distance substantially equalling the length of the metallic tubes containing the cork rods, a stay rod supporting said plates and holding them rigidly in relation to each other, one of said plates having a slot formed in that face thereof presented toward the other plate, and a stud carried by the other plate having a reduced stem and projecting toward said slotted plate, whereby a tube may be mounted in said carrier by inserting the empty end thereof over said stud until the head of the stud is in substantial engagement with the cork composition of the tube, and dropping the other end of said tube into

said slot with a pivotal movement of the tube about said stud.

4. A carrier for cork rod bakers embodying therein carrier members, oppositely disposed plates carried thereby and spaced apart a distance substantially equalling the length of the metallic tubes containing the cork rods, one of said plates having a slot formed in that face thereof presented toward the other plate, and a stud carried by the other plate projecting toward said slotted plate, said stud having a reduced stem and a circular head of a diameter to have a loose fit within a tube and of reduced dimensions towards said stem to form a fulcrum point about said head to permit a tube to be brought to an angular relation to the stud, whereby a tube may be mounted in said carrier by inserting the empty end thereof over said stud until the head of the stud is in substantial engagement with the cork composition of the tube, and dropping the other end of said tube into said slot with a pivotal movement of the tube about said stud.

5. A carrier for cork rod bakers embodying therein carrier members, oppositely disposed plates carried thereby and spaced apart a distance substantially equalling the length of the metallic tubes containing the cork rods, and a plurality of tiers of studs upon one of said plates, each of said studs having a reduced stem and a circular head of a diameter to have a loose fit within a tube and of reduced dimensions towards said stem to form a fulcrum point about said head to permit a tube to be brought to an angular relation to the stud, and said other plate having a plurality of slots therein oppositely disposed respectively to a row of studs included in the different tiers, whereby tubes may be mounted in said carrier by inserting the empty end of each over a stud until the head of the stud is in substantial engagement with the cork composition of the tube, and dropping the other end of said tube into said slot with a pivotal movement of the tube about said stud.

6. A carrier for cork rod bakers embodying therein oppositely disposed sprocket chains, brackets carried by opposite links in said chains, a stay rod carried by said brackets, oppositely disposed plates carried thereby and spaced apart a distance substantially equalling the length of the metallic tubes containing the cork rods, and a plurality of tiers of studs upon one of said plates, each of said studs having a reduced stem and a circular head of a diameter to have a loose fit within a tube and of reduced dimensions towards said stem to form a fulcrum point about said head to permit a tube to be brought to an angular relation to the stud, and said other plate having a plurality of slots therein oppositely disposed respectively to a row of studs included in

- the different tiers, whereby tubes may be mounted in said carrier by inserting the empty end of each over a stud until the head of the stud is in substantial engagement with
5 the cork composition of the tube, and dropping the other end of said tube into said slot with a pivotal movement of the tube about said stud.

In witness whereof I have hereunto affixed my signature, in the presence of two sub-¹⁰scribing witnesses, this 18th day of May, 1921.

CHARLES E. McMANUS.
